UNITED STATES PATENT OFFICE.

MARY LAWSON NEFF, OF NEW YORK, N. Y.

SANITARY DRINKING-CUP.

1,002,537.

Specification of Letters Patent. Patented Sept. 5, 1911.

Continuation in part of application filed April 20, 1911, Serial No. 622,323. This application filed May 15, 1911. Serial No. 627,139.

To all whom it may concern:

Be it known that I, MARY LAWSON NEFF, a citizen of the United States, and a resident of the borough of Manhattan, city, 5 county, and State of New York, have invented certain new and useful Improvements in Sanitary Drinking-Cups, of which the following is a specification.

This application is a continuation in part 10 of the prosecution of my abandoned application Serial No. 622,323, filed April 20th, 1911.

The object of the present invention is to produce a simple, cheap and convenient 15 form of sanitary drinking cup which is intended to be used once and then thrown away. Such sanitary drinking cups are particularly adapted for distribution from automatic vending machines placed near 20 public drinking fountains.

My improved sanitary drinking cup is formed of a single blank of suitable material folded upon itself in such manner as to form a double-walled body with integral 25 ears presented in convenient position to serve as a handle for the cup and by which the cup is retained in shape for use. The blank from which the cup is made is preferably of such size and shape that it can 30 first be folded upon its longest diameter to produce a double-walled body with edge flaps projecting from the body walls, so that upon folding the opposite wings of the double-walled body inwardly toward each other 35 and then bending the extreme ends of said wings outwardly into handle ears, the said flaps can be bent downwardly upon the front and rear walls of the cup body to form a sanitary drinking edge for the front wall 40 and a strengthening and retaining edge for the rear wall. The flap which is bent down upon the rear wall of the cup body is centrally divided to fit upon opposite sides of the integral handle ears so that in taking the 45 cup between the thumb and first finger, these sections of the rear edging flap can be pinched at their corners against the handle ears with the result that the cup will be automatically sprung open in readiness to 50 be filled with water. The flap which is turned down upon the front wall of the drinking cup forms a smooth folded drinking edge for the cup which cannot possibly injure the lips, and since the cup is auto-

matically opened in the manner explained, 55 this drinking edge need not be touched with the fingers so that its sanitary condition can be absolutely insured. Aside from the downwardly folded front and rear flaps affording smooth edges to the walls of the 60 cup, they serve to materially strengthen the cup by reason of the extra thickness of the material.

In the preferred form of my improved drinking cup, the oppositely extending 65 wings of the once folded blank are folded inwardly upon the body on lines inclined outwardly from the bottom, so as to produce a cup with outwardly flaring edges and with the open top of the cup of greater width 70 than the closed bottom. This form of the cup is preferred not only because of the greater capacity of cup from a given size blank, but also because the cup in this form is more convenient to manipulate. While, 75 however, the preferred form of cup has the peculiarities noted, I would have it understood that my invention in its simplest form includes essentially only the double-walled body having the integral inwardly folded 80 wings with out-turned ends to constitute a handle for the cup.

In order that my invention may be fully understood, I will first describe the same with reference to the accompanying drawings, 85 and afterward point out the novelty more particularly in the annexed claims.

In said drawings: Figure 1 is a perspective view illustrating the preferred form of my improved sanitary drinking cup in position for use. Fig. 2 is a plan view of a cut blank from which the form of cup shown in Fig. 1 is produced, the folding lines being indicated by dotted lines. Figs. 3, 4, 5 and 6 illustrate the successive stages of folding 90 the blank of Fig. 2 into the completed cup shown in Fig. 1. Fig. 7 is a plan view of a modified form of blank for producing a simpler form of cup embodying my invention, the folding lines being indicated by 95 dotted lines. Fig. 8 is a perspective view of a completely folded cup produced from the form of blank shown in Fig. 7.

In producing my improved sanitary drinking cup in its most practical 105 form, I employ a blank substantially of the form shown at 1 in Fig. 2. This blank is approximately square, with

two of its diagonally opposite corners trimmed off, one in a straight line as shown at 2, and the other rounded off as shown at 3. These trimmed off portions of the blank 5 constitute the flaps for the front and rear walls of the cup by folding them upon the lines 7 and 8 respectively as hereinafter more fully explained. The rear wall flap is centrally cut on the line 5 between the edge 10 and the folding line 7 to form flap sections a and a'.

In forming the cup, the blank 1 is first folded upon its longest diameter indicated by the dotted line 6, to produce a double-walled or once folded blank as shown in Fig. 3 of the drawings. In this once folded condition of the blank, the flap fold lines 7 and 8 will be coincident and the front wall flap 4 will project beyond the rear wall flap 20 a, a'. The triangular end wing ABC of the once folded or double-walled blank is then folded inwardly upon the body on the line 9 which flares outwardly from the bottom fold line 6 to the end of the flap fold lines 7 25 and 8. The rear wall flap section a is then bent downwardly on line 7 upon the in-folded wing ABC to place the partly folded blank in the form shown in Fig. 4 of the drawings. The opposite end wing DEF is then folded inwardly upon the double-walled body on the line 10 flaring outwardly from the bottom fold line 6 to the flap fold lines 7 and 8 and the second rear wall flap section a' is bent over into engagement with 30 said folded wing DEF. The extreme ends b and b' of wings ABC and DEF are then bent outwardly upon the lines 11 which in the described folded condition of the blank will practically coincide with the line of cut 35 5 which separates the rear wall flap into sections a and a'. These ends are ears b, b' constitute the handle for the cup as will presently be explained. The blank will then appear in the form shown in Fig. 5. The final 40 step in completing the cup is in folding down the front wall flap 4 upon the front wall of the folded cup as shown in Fig. 6.

The completely folded cup produced as described is presented to the person in folded flat form and is grasped with the handle ears b, b' and the adjacent corners of the flap sections a, a' between the thumb and fingers, as shown in Fig. 1 of the drawings.

A slight pressure upon the corners of flap 55 sections a, a' will cause the cup to be sprung open in readiness to be filled with water, and when so filled, the cup, held as described, can be conveniently supported and placed to the lips with the folded edge of the front wall making a smooth and convenient drinking edge. Since the cup is opened automatically when it is picked up as described, it is 60 unnecessary for a person to touch the drinking edge of the cup so that the sanitary condition of the drinking edge is maintained.

In Figs. 7 and 8 I have shown the simplest form in which my improved drinking cup may be made, embodying all of the essential features of my invention. In this form of cup I take a rectangular blank such as 25, 70 having oblong flaps 26 and 27 projecting centrally from its opposite sides. The flap 26 is designed to be folded on the dotted line 26^a while the flap 27 is designed to be folded on the dotted line 27^a. The flap 27 is centrally divided by a slit 28. The blank is first folded upon the central longitudinal line 30, then the opposite double-walled end wings are folded inwardly on the lines 31 and 32 and the extreme ends of these wings are 80 folded outwardly upon the lines 33 and 34. These outwardly folded extreme ends constitute rectangular handle ears 35 and 36, each of which is of a double thickness of material. The divided rear wall flap 27 is 85 then folded down over the inwardly folded double end wings upon opposite sides of the outwardly presented ears or handles 35 and 36 and the front wall flap 26 is then folded downwardly upon the front wall of the 90 folded cup to complete the same. The cup thus produced is approximately square in shape, with the side edges extending at right angles to the bottom edge. This cup embodies the essential features of my invention 95 and will operate in the same manner as described with reference to the preferred form in which the cup has a flaring cup body, but because of the rectangular form of this modified form of the cup, it is not so 100 convenient or satisfactory to manipulate.

My improved folded sanitary drinking cups can be conveniently packed in a relatively small space until used. They can be readily handled in an automatic vending machine, they being substantially flat in shape when collapsed and requiring a minimum amount of room to accommodate them. The improved cup is simple and cheap to manufacture, very convenient to use and absolutely sanitary because of the facility for handling it without the necessity of placing the fingers upon the drinking edge of the cup. The downturned flaps for the front and rear walls of the cup do away 110 with the objectionable sharp edges of the cut blank, they strengthen the cup, and in the case of the flap for the rear wall, serve as a means for automatically opening the cup to receive water by the act of taking 115 hold of the handle ears.

My improved sanitary drinking cup may be made of any suitable material, but I prefer to make it of a suitable water-proofed paper such as wax paper. The improved cup does not require adhesive or other fastening means for holding it in shape for use, since the described folded formation insures the retention of the cup in proper 125 shape to be filled and used when it is 130

grasped by the handle ears. The absence of adhesive is important from both the manufacturing and sanitary standpoints.

So far as I am aware, I am the first to produce a folding cup made of a single blank of material folded upon itself and with its opposite double-walled wings folded inwardly upon the body portion and the ends of said infolded wings bent outwardly to constitute a handle. So far as I am aware, I am also the first to construct a folding cup with the edges formed by downwardly folded flaps upon the front and rear walls, or a cup with an integral handle and a split rear wall flap coöperating with the handle and serving as a means for automatically opening the cup. I desire to claim these features in a broad sense.

I would have it understood that in the formation of the improved cup, the angle upon which the end wings are folded in upon the body may be varied for changing the shape of the cup, and that the handle ears may be variously shaped by slightly changing the shape of the extreme ends of the double-walled wings. These minor details are not material to the scope of my invention. In the manufacture of the cup, the lines of fold may be scored to facilitate the folding operations.

What I claim is:

1. A drinking cup made of a single piece of material folded upon itself to form a double-walled body, and having its oppositely projecting double-walled wings folded inwardly upon the body and bent outwardly at their ends to constitute a handle.

2. A drinking cup made of a single piece of material folded upon itself to form a double-walled body and having its oppo-

sitely projecting double-walled wings folded inwardly against the body upon lines inclined outwardly from the bottom to form a flaring cup and the ends of said wings bent outwardly from the body upon lines approximately at right angles to the bottom to form a handle. 45

3. A drinking cup comprising an elongated blank folded longitudinally upon itself to form a double-walled body having 50 oppositely projecting double-walled wings, and integral flaps extending respectively from the front and rear walls, said double-walled wings being folded inwardly upon the body portion and having their ends bent 55 outwardly from the body portion to constitute handle ears, and the end flaps being bent downwardly upon the front and rear walls respectively of the body portion, the flap of the rear wall being split to rest upon 60 opposite sides of said handle ears, substantially as set forth.

4. A drinking cup of the character described, formed of a substantially square blank folded diagonally upon itself, and the 65 opposite triangular base wings folded inwardly toward each other with the extreme ends *b*, *b'* folded outwardly to form a handle for the cup, whereby the folding edges of said extreme ends *b*, *b'* will be parallel and 70 adjacent to each other, the remaining top portion *a*, *a'* of the diagonally folded blank being split intermediate the ends of and at right angles to its edge and each half being folded over the inwardly folded base 75 wing adjacent to it.
